United States Patent Office

Des. 233,918
Patented Dec. 17, 1974

233,918

TRANSIT SEAT

Chester J. Barecki, Grand Rapids, Mich., assignor to
American Seating Company, Grand Rapids, Mich.

Continuation-in-part of design application Ser. No.
238,744, Mar. 27, 1972. This application May 11, 1973,
Ser. No. 359,304

Term of patent 14 years

Int. Cl. D6—01

U.S. Cl. D6—26

FIG. 1

FIG. 2

FIG. 3

FIG. 4

FIG. 5

FIG. 6

FIG. 7

FIG. 8

FIG. 9

FIG. 1 is an upper frontal perspective view of the inventive seat;

FIG. 2 is an upper rear perspective view of the seat of FIG. 1;

FIG. 3 is a view similar to FIG. 2 of the inventive seat without a rear cover;

Figs. 4-6 are respectively, top plan, front elevation, and side views of the seat;

FIG. 7 is an upper frontal perspective view of an alternative embodiment of the inventive seat;

FIG. 8 is a front elevation view of the seat of FIG. 7; and

FIG. 9 is a side view of the seat of FIG. 7.

I claim:

The ornamental design for a transit seat, as shown and described.
